UNITED STATES PATENT OFFICE.

HARRY W. MOIR, OF LOS ANGELES, CALIFORNIA, ASSIGNOR OF ONE-HALF TO LESTER H. MILES, OF LOS ANGELES, CALIFORNIA.

CARBURETOR CUT-OFF.

Application filed April 20, 1920, Serial No. 375,380. Renewed April 18, 1925.

To all whom it may concern:

Be it known that I, HARRY W. Moir, a citizen of the United States, and a resident of Los Angeles, county of Los Angeles, and 5 State of California, have invented a new and useful Improvement in Carburetor Cut-Offs, of which the following is a specification; the principle of the invention being herein explained and the best mode in which I have 10 contemplated applying that principle, so as to distinguish it from other inventions.

The present invention, relating, as indicated, to carburetor cut-offs, is more particularly directed to a device for use in connection with a carburetor for an internal combustion engine for the purpose of disconnecting the carburetor from the intake manifold of the engine. It is desirable at times to entirely disconnect the carburetor from the 15 engine to prevent the wastage of gasoline, as when, for example, a vehicle is coasting down hill with the engine acting as a brake. In such a situation the engine, instead of operating the vehicle is being in turn operated by the rotation of the vehicle wheels, and under such conditions the ignition is usually switched off and the compression in the cylinders acts to brake against the movement of the vehicle. In mountainous 20 country this is a very common way of braking a car, and sometimes for periods of minutes at a time the engine is being operated by the car, but without the combustion of any gasoline. At such times gasoline 25 vapor is drawn through the engine as if the engine were operating, but all of this gasoline is entirely wasted. The carburetors in common use are not provided with any means for disconnecting them from the 30 engine, and it is to provide a simple means for convenient attachment to the carburetor that the present invention has been developed. To the accomplishment of the foregoing and related ends, said invention, 35 then, consists of the means hereinafter fully described and particularly pointed out in the claims.

The annexed drawing and the following description set forth in detail certain mechanism embodying the invention, such disclosed means constituting, however, but one

of various mechanical forms in which the principle of the invention may be used.

In said annexed drawing:

Fig. 1 is a side elevation of an internal 55 combustion engine mounted in a motor vehicle with my invention applied thereto; Fig. 2 is a side elevation of my device; Fig. 3 is a side elevation of the operating means for the device; Fig. 4 is a plan view of the 60 device; Fig. 5 is a plan view with the cover plate removed showing the mechanism in inoperative position; Fig. 6 is a similar view, but showing the mechanism in operative or 65 closed position; and Fig. 7 is a section on the line 7—7, in Fig. 6.

In Fig. 1 I have shown a cylinder block 1 of an internal combustion engine, to which is attached the usual intake manifold 2, which terminates in a single vertical conduit 3. A carburetor 4 is ordinarily attached directly to the lower flanged end of a conduit 3, and my device is adapted to be interposed between the carburetor and the manifold. My device comprises a chamber 75 formed by two spaced plates 6 and 7, provided with openings 8 for the passage of the bolts which fasten the device between the manifold and the carburetor. Between the plates 6 and 7 is formed a passage 9 of 80 the same size and adapted for registration with the passage through the lower end of the manifold and the mixing chamber of the carburetor 4.

Pivotedly mounted about an axis in the 85 form of a stud 10 is a valve member 11, which is shown in its operative position in Fig. 5, but which may be swung into the position shown in Fig. 6 when it will entirely close the passage through my device 90 and thus disconnect the carburetor from the manifold. Operation of the valve is secured by means of a link 12 mounted exteriorly of the device on the projecting end of the stud 10 and connected by a wire or rod 13 to an operating handle 14, which is suitably mounted on the dash or foot board 15 of the vehicle. This operating wire or rod is slidably disposed in an enclosing tube or casing 16 mounted on the 95 foot board 15 at one end and in a projection 18 on the device at its other end.

The plates 6 and 7 are provided with a lateral opening 20 extending from the exterior to the passage 9 and this opening is normally closed by means of a pivoted valve 21 mounted about a pin 22 on the outside of the casing and held in closed position by means of a spring 23, one end of which is received in a socket 24 formed in the plates 6 and 7. This valve 21 is operated at the same time as the valve 11, the latter being provided with a projecting arm 25 which is forced against the valve 21 when the valve 11 is moved into the position shown in Fig. 6, and thus serves to push the valve 21 open. Air is then admitted through the opening 20 from the atmosphere to the passage in the manifold, the air passing through the opening 20 and then over a beveled-off edge portion 26 on one side of the valve member 11. Thus, when the valve 11 is in position to disconnect the carburetor from the manifold it has opened the valve 21 and air is then drawn into the manifold from the atmosphere, in this way permitting the engine to operate in the usual way, and to give its full braking effect on the vehicle because of the compression of the air which is drawn in in this manner.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. A device adapted to be interposed between the carburetor and intake manifold of an internal combustion engine, said device comprising a chamber having a longitudinal opening therethrough, and a second opening to the atmosphere, a valve movable transversely of such longitudinal open-

ing to close the same, and a second valve mounted externally of said apparatus and normally closing such second opening, said first-named valve being adapted to engage and open said second valve upon the closing of said first-named valve.

2. A device adapted to be interposed between the carburetor and intake manifold of an internal combustion engine, said device comprising a chamber having a longitudinal opening therethrough, and a second opening to the atmosphere, a valve adapted to close such opening through said chamber, and a second valve normally closing such second opening, said first-named valve being adapted to engage and open said second valve upon the closing of said first-named valve, and said first-named valve member being formed with a passage connecting with such second opening in said chamber in the closed position of said valve, such passage leading to such opening through said chamber on one side of said valve controlling the same.

3. A device adapted to be interposed between the carburetor and intake manifold of an internal combustion engine, said device comprising a chamber having a longitudinal opening therethrough, and a second opening to the atmosphere, a valve adapted to close such opening through said chamber, and a second valve normally closing such second opening, said first-named valve being adapted to engage and open said second valve upon the closing of said first-named valve, said first-named valve member being formed with a passage connecting with such second opening in said chamber in the closed position of said valve, such passage leading to such opening through said chamber on one side of said valve controlling the same.

Signed by me this 14th day of Apr., 1920.

HARRY W. MOIR.
